LIVIN STAS, OF TACOMA, WASHINGTON.

AIR-DRILL HANGER.

1,150,312.

Specification of Letters Patent. Patented Aug. 17, 1915.

Application filed October 28, 1914. Serial No. 868,965.

To all whom it may concern:

Be it known that I, LIVIN STAS, a citizen of the United States, and a resident of Tacoma, in the county of Pierce and State 5 of Washington, have invented certain new and useful Improvements in Air-Drill Hangers, of which the following is a specification.

This invention relates to devices for holding a drill while it is in use, and is especially adapted for use with an air-drill, though it may also be used with an electric or with a ratchet-drill.

The objects of this invention are to provide a device whereby the drill may be firmly held in place while in use and whereby, when the material being drilled is pierced, the drill and its apparatus will be held steadily in place and will not be suddenly pushed through the hole just drilled, thereby saving the breakage of many drills.

Other objects are to reduce the cost of drilling holes by reducing the number of men needed to handle the air-drill and reducing the time needed to drill through the material.

I attain these and other objects by the devices, mechanisms, and arrangements illustrated in the accompanying drawing, in 30 which—

Figure 1 is a side elevation showing my device in use; and Fig. 2 is a side elevation of the hanger, showing a part thereof in section to reveal its construction.

Similar numerals of reference refer to similar parts throughout the several views.

One of the difficulties incident to drilling holes with an air-drill is found in the fact that when the material is pierced by the 40 drill the men controlling it have to be very alert to prevent its sudden passage through the hole thus breaking it off in the hole. For this reason it is found necessary at present to have two or three men handle each 45 drill, and even then many drills are broken and great care must be exercised by the men. It is with a view of overcoming this objection that I have invented the following described hanger which converts the hand air-drill practically into a drill-press.

A post 1 is secured in any handy way to the work to be drilled, or to the table or other surface. This post 1 has an arm 2 extending from it at right angles, said arm 55 being adjustable to any desired point in the

post and to extend in any direction therefrom.

The hanger 3 to which the drill is attached is provided with an opening 4 in one edge, said opening forming a pair of jaws adapted to receive the said arm 2 between them. A set screw 5 passes through the upper jaw 6 and engages the upper surface of the arm 2, thus drawing the lower jaw 7 into engagement with the lower edges of the arm 2. 65 The lower jaw 7 is formed slightly V-shaped as shown. The hanger is also provided with a handle 8 in a convenient position thereon. The part 7 of the hanger extends downward and has a screw-threaded extension 9 at its lower end. A semi-spherical recess or socket 10 of suitable diameter is formed in said downward extension 9. A nut 11 is screwed on said extension 9 and has a complementary semi-spherical recess or socket 12 70 formed in it, said parts being such that when the nut is screwed into place the two sockets 10 and 12 adjoin and form a spherical socket. A hole 13 leads through the nut 11 to the socket 12. A spherical ball 14 fits 75 in said socket and is free to turn therein. The ball 14 has a screw-threaded hole extending up into it. A union 15 has a threaded upward extension screwed into said hole in the ball 14, and also has a similar screw-threaded hole in its lower end. The screw 16 at the upper end of the air-drill enters the hole in the union 15.

The air-drill 17 is provided with handles 18 and with a feed screw 19, whereby the 80 apparatus and drill 20 are pressed down or are raised up.

It is evident from the drawings and description that the drill is held from any longitudinal motion except as it is fed in 95 either direction by turning the handles of the feed screw 19, and that when the resistance of the material being drilled ceases (because the drill has pierced the material) the apparatus will remain in its position and 100 the drill can be withdrawn at once by reversing the feed. Also, it will be noted that a considerable swing is allowed in the ball and socket joint so that if the angle of the hole is not at right-angles to the arm 105 2, the difference will be taken up in the ball and socket joint. It is evident that my apparatus renders the operation of air-drilling as safe and economical as in the usual drill press and yet can be used in an un- 110

limited number of circumstances in which the drill press could not be used.

Having described my invention, what I claim is:

- 5 In a drill hanger, the combination with an arm; a frame clamped to said arm; a ball and socket joint formed in said frame; a drilling machine having a longitudinal

feed; and a union piece removably screwed into said ball and socket joint and to the 10 drilling machine.

LIVIN STAS.
